UNITED STATES PATENT OFFICE

PAUL SCHMALJOHANN, OF KIEL, GERMANY, ASSIGNOR TO CENTRA HANDELS- & INDUSTRIE A.-G., OF CHUR, SWITZERLAND, A CORPORATION OF SWITZERLAND

TWO-STROKE CYCLE INTERNAL COMBUSTION ENGINE

Application filed January 3, 1930, Serial No. 418,317, and in Germany January 5, 1929.

My invention relates to improvements in two-stroke cycle internal combustion engines, and more particularly in engines of the type comprising a plurality of cylinders disposed 5 radially of one another and having a common central combustion chamber. In engines of this type the pistons or plungers are formed at their inner ends with gable roof-shaped bottoms, for reducing as far as possible the 10 size of the combustion chamber, which is particularly important in engines of the Diesel type the combustion chamber of which must be as small as possible.

In two-stroke cycle engines of this type in 15 which the scavenging ports are disposed all around the circumference of the cylinder the said gable roof-shaped form of the pistons interferes with scavenging, the said gable roof-shaped bottoms deflecting the scaveng- 20 ing air injected into the cylinders through the said ports towards the axial portions of the cylinders, so that in the outer portions whirls are produced and the scavenging is unsatisfactory.

25 The object of the improvements is to provide an engine in which this objection is obviated, and with this object in view my invention consists in disposing the intake ports for scavenging air exclusively along the inclined margins of the bottoms of the pistons and so that the scavenging air is injected into the cylinders in a direction substantially parallel to the ridges or meeting portions of the gable roof-shaped faces of the bottoms of the 30 pistons. When thus disposing the intake ports the currents of scavenging air injected into the cylinders impinge upon each other without being deflected by the gable roof-shaped bottoms of the pistons, and the kinetic 35 energy of the said currents is largely annihilated, so that the cylinders are completely filled with scavenging air, and the said air acts in the manner of pistons filling out the 40 whole cross-sectional areas of the cylinders 45 and scavenging the combustion gases from the same.

In the preferred construction the scavenging ports are disposed longitudinally of the cylinders so that they are completely un- 50 covered by the pistons, and so that when

moving outwardly the said pistons pass slightly beyond the same, so that during a considerable part of the scavenging period the controlling edges of the pistons do not deflect the currents of scavenging air, and the 55 currents of scavenging air rush into the cylinders in directions parallel to the faces of the bottoms of the pistons.

For the purpose of explaining the invention an example embodying the same has been 60 shown in the accompanying drawings in which the same reference characters have been used in all the views to indicate corresponding parts. In said drawings,

Fig. 1 is a sectional elevation of the 65 engine,

Fig. 2 is a detail longitudinal sectional elevation on an enlarged scale showing a part of one of the cylinders,

Fig. 3 is a longitudinal sectional elevation 70 taken on the line 3—3 of Fig. 2, and

Fig. 4 is a cross-sectional view taken on the line 4—4 of Fig. 3 and looking in the direction of the long arrow.

In the example shown in the figures the 75 two-stroke cycle internal combustion engine may be assumed to operate on the Diesel principle, and it comprises three cylinders *a* disposed radially of each other and connected or made integral with one another at their 80 inner ends to provide a combustion chamber *c*. Within the cylinders pistons *b* are mounted the bottoms of which are gable roof-shaped, the said bottoms comprising outer portions *d* inclined relatively to each other 85 and to the axes of the cylinders and rounded or ridge portions *e* connecting the said inclined portions. While the term "gable roof-shaped" is used herein to define the shape of the outer end of the pistons, it will be 90 understood that this expression is used only for convenience and brevity. The actual preferred shape comprises two substantially plane surfaces inclined to one another and joined by a curved portion, or ridge, 95 as best shown in Figs. 2 and 4, or even a cylindrical-convex or vaulted shape as shown in Figs. 1 and 3, and for want of a better term the expression "gable roof-shaped" in this specification and claims is to be under- 100

stood as including all such shapes. Thus, when the pistons are at their inner dead centre positions the said gable roof-shaped bottoms reduce the volume of the combustion chamber.

5 The scavenging ports *f* of the cylinders *a* are disposed parallel to the portions *e* of the bottoms of the pistons and to the faces *d*, and they extend over a part only of the circumference of the cylinders, as is best 10 shown in Fig. 4. Thus, there are two groups of scavenging ports *f* which are opposed to each other, and which are located at the parts of the cylinders adjacent to the inclined margins of the faces *d* and *e*. Further, the slots *f* are disposed so that the controlling edges follow the form of the gable roof-shaped bottoms *d*, *e* of the pistons, as is shown in Fig. 3. Therefore, all the ports 15 *f* are simultaneously uncovered by the pistons *b*.

With reference to the outer dead centre positions of the pistons *b* the scavenging ports *f* are disposed in the cylinder *a* so that 20 in the outer dead centre positions of the pistons the controlling edges of the piston bottoms *d*, *e* are at a distance *x* from the outer edges of the ports *f*.

In the example shown in the figures in 25 two of the cylinders *a* the ports *f* act as scavenging ports, while in the third cylinder the ports *g* act as exhaust ports.

When the scavenging ports *f* of the cylinders *a* are uncovered by the pistons *b* moving outwardly air is injected through the 30 said ports into the cylinders, the currents of air being parallel to the ridges *e* and the faces *d* of the bottoms of the piston. Therefore the said currents of air are not deflected 35 by the gable roof-shaped bottoms, and the currents of air injected through the opposing groups of ports *f* impinge upon each other so that their kinetic energy is largely 40 annihilated, and the portion of the cylinder 45 *a* located internally of the bottoms *d*, *e* is completely filled with scavenging air. By the following scavenging air the said air is driven into the cylinders *a* filling out the 50 whole cross-sectional areas thereof and acting as air pistons driving out the combustion gases through the slots *g*.

After the scavenging ports *f* have been completely uncovered by the pistons *b* the 55 said pistons continue their outward stroke through a distance *x* shown in Fig. 3, and upon the following inward stroke of the pistons *d*, *e* the controlling edges of the bottoms of the said pistons begin to cover the outer edges of the scavenging ports only after they 60 have performed the portion *x* of their stroke. Thus during the major part of the scavenging period the controlling edges of the pistons *b* are away from the scavenging ports *f*, so that during the said portion of the period 65 the currents of air injected through the

ports *f* are not deflected by the edges of the pistons.

The improvements may be used in two-stroke cycle internal combustion engines comprising three or more pistons and having a common combustion chamber.

I claim:

1. A two-stroke cycle internal combustion engine, comprising more than two cylinders disposed radially of one another and having a common central combustion chamber, pistons reciprocating in said cylinders and having gable roof-shaped inner bottoms, and two similar and oppositely located groups of scavenging ports disposed parallel to the ridges or meeting portions of the gable roof-shaped portions of the inner faces of the bottoms of the pistons, said groups being located at the opposite gable sides.

2. A two-stroke cycle internal combustion engine, comprising more than two cylinders disposed radially of one another and having a common central combustion chamber, pistons reciprocating in said cylinders and having gable roof-shaped inner bottoms, and two similar and oppositely located groups of scavenging ports disposed parallel to the ridges or meeting portions of the gable roof-shaped portions of the inner faces of the bottoms of the pistons and at the opposite gable sides of the pistons and so disposed that all the ports are uncovered simultaneously by the pistons.

3. A two-stroke cycle internal combustion engine, comprising more than two cylinders disposed radially of one another and having a common central combustion chamber, pistons reciprocating in said cylinders and having gable roof-shaped inner bottoms, and two separate groups of scavenging ports located at the gable sides and disposed parallel to the ridges or meeting portions of the gable roof-shaped portions of the inner faces of the bottoms of the piston, said ports being so disposed relatively to the pistons and axially of the cylinders that in the outer dead centre positions of said pistons the leading edges thereof are spaced from the outer edges of said ports.

In testimony whereof, I affix my signature.

PAUL SCHMALJOHANN.
